Primary Examiner—Brian N. Vinson(74) *Attorney, Agent, or Firm*—John J. Murphey(57) **CLAIM**

The ornamental design of a straight key tag rack, as shown and described.

DESCRIPTION

FIG. 1 shows a front perspective view of a two-unit straight key tag rack showing my new design;

FIG. 2 is a front elevational view of the design shown in FIG. 1;

FIG. 3 is a rear elevational view of the design shown in FIG. 1;

FIG. 4 is another embodiment of my invention and shows a front perspective view of a six-unit straight key tag rack showing my new design;

FIG. 5 is a front elevational view of the design shown in FIG. 4;

FIG. 6 is a rear elevational view of the design shown in FIG. 4;

FIG. 7 is another embodiment of my invention and shows a front perspective view of a ten-unit straight key tag rack showing my new design;

FIG. 8 is a front elevational view of the design shown in FIG. 7; and,

FIG. 9 is a rear elevational view of the design shown in FIG. 7.

The broken-line disclosure of key tags in the views are for illustrative purposes only and form no part of the claimed design.
